UNITED STATES PATENT OFFICE.

FREDERIC S. SEAGRAVE, OF ROCHESTER, MICHIGAN.

LADDER.

SPECIFICATION forming part of Letters Patent No. 278,051, dated May 22, 1883.

Application filed November 8, 1882. (No model.)

To all whom it may concern:

Be it known that I, FREDERIC S. SEAGRAVE, of Rochester, in the county of Oakland and State of Michigan, have invented new and useful Improvements in Ladders; and I do hereby declare that the following is a full, clear, and exact description thereof, reference being had to the accompanying drawings, which form a part of this specification.

10 The nature of this invention relates to certain new and useful improvements in ladders, by means of which a very light, strong, and durable ladder is constructed.

15 The invention consists in the peculiar construction of parts and their combination, as more fully hereinafter described.

Figure 1 is a perspective view of my improved ladder. Fig. 2 is a side elevation, showing the method of constructing each leg 20 of the ladder, with its truss, from a single piece of lumber.

25 In the accompanying drawings, which form a part of this specification, A represents the legs of a ladder, which are joined together by the rounds B in the usual manner. C is the truss with which each leg is provided, and D are the struts.

The peculiarity of this ladder is in the construction of the legs and trusses. In Fig. 2 30 there is shown a straight piece of timber, of the desired length of the ladder, near one end, and at the rear end of this piece there is bored a small hole, a, through which a saw is inserted, which cuts the saw-kerf b, which extends nearly to the opposite end of this piece 35 of timber. This rear piece thus partially detached from the main piece of the leg is thinner than and forms an integral part of the leg itself, and bolts c are inserted through the leg 40 from front to rear, just at the ends of the saw-kerf, to prevent splitting at that point. The two legs being thus prepared, and being joined together by the rounds, the struts are inserted

between the leg proper and the truss, the longer one at a nearly-central position between 45 the two ends, and the shorter ones intermediate between the longer strut and the ends of the legs, and these struts are secured in position in any convenient way, so that when the ladder is completed the leg proper will have 50 a slight camber or curve to the front, and be very strongly braced against pressure by the strusses thus formed.

I am aware that it is not new to make trussed ladders; and I am also aware that light and 55 very strong ladders are made which are trussed with wire, which makes them more expensive in construction and less firm than when made as I have before described, for such wire trusses will stretch, or, to use a technical 60 phrase, "give and take"—a fault which is entirely avoided by my construction.

An ordinary painter's ladder twenty-five feet long requires sixty feet of lumber to construct it, while an equally strong but much 65 lighter ladder can be made, by the construction herein described, of the same length with fifteen feet of lumber.

What I claim as my invention is—

1. The combination, in a ladder, of the rounds 70 B and legs A, each leg being provided with a kerf, b, back of its center, and extending nearly to the ends thereof, forming a thin back or brace, C, whereby the front A, or leg proper, is left sufficiently thick for the insertion of the rounds B, as set forth.

2. A ladder constructed of sides or legs A, having a brace, C, formed by a kerf, b, in the leg, back of its center, as shown and described, 75 rounds B, struts D, and bolts e, all constructed 80 and arranged substantially as shown and described.

FREDERIC S. SEAGRAVE.
